SIGNALING

Murray G. Crosby, Riverhead, N. Y., assignor to
Radio Corporation of America, a corporation
of Delaware

Original application June 20, 1932, Serial No.
618,154. Divided and this application October
23, 1940, Serial No. 362,331

12 Claims. (Cl. 179—171)

This is a division of my copending application Serial No. 618,154, filed June 20, 1932, now U. S. Patent No. 2,229,640, dated January 28, 1941.

My present invention relates to frequency and phase modulation systems and apparatus. One object of my invention is to provide circuits, methods and apparatus generally useful for phase and frequency modulated waves. Other objects as well as advantages flowing from my invention will appear as the more detailed description thereof proceeds.

In the drawings Figs. 1 and 2 are curves explanatory of my present invention; and

Figs. 3, 4, 5, 6 and 7 illustrate filter circuits which may be included in the frequency modulated signal receivers of the prior figures to adapt them to efficient reception of phase modulated signals.

As explained in my copending application referred to above, frequency modulation wave directors may, in accordance with the present invention, be used for the reception of phase modulation waves. This is accomplished by adjusting the circuits for frequency modulation, as described in my parent application, and using a correcting filter or circuit at the receiver which has its output voltages inversely proportional to its input frequency so that its characteristic is as shown in Fig. 1, wherein audio frequency impressed on the input terminals of the correction circuit is plotted against voltage output.

When phase modulated signals are received on a frequency modulation receiver, the signal output of the frequency modulated receiver varies in amplitude directly with the frequency of the signal at the input of the frequency modulated signal receiver. Consequently, the audio frequency output of this receiver would be distorted and would be lacking in low frequencies. The output of the receiver instead of being the same for all audio frequencies, as shown by the dotted line of Fig. 2, would be directly proportional to the frequency of the signals impressed on the input of the receiver, as shown by the full line of Fig. 2.

In order to compensate for this distortion of the signal frequency when phase modulated signals are received on a frequency modulated signal receiver, a filter circuit or correction circuit, the amplitude of the signal frequency in the output of which is inversely proportional to the frequency of the signals impressed on the input of the circuit, as indicated in Fig. 1 of the drawings, is utilized in accordance with the present invention to adapt a frequency modulated re-

ceiver for reception of phase modulated signals. The combination of the effect of a filter circuit or correction circuit having characteristics as illustrated by Fig. 1, with the effect of the inherent characteristics of a frequency modulated receiver on phase modulated signals, gives an over-all characteristic such as the dotted line of Fig. 2, which is a true reproduction of the signal wave applied as phase modulation to the carrier at the transmitter.

This correction filter or circuit CC is used with the receiver and is connected after the detector as described in detail in my parent application.

Various forms of filter or correction circuits, which will affect the signal frequencies passed therethrough in such a manner as to make the amplitude of the signals at the output thereof inversely proportional to the frequency of the signals applied to the input, may be used. Several preferred forms of correction circuits will now be described.

In Fig. 3 phase modulated waves picked up on the antenna are translated into signal waves by the frequency modulation receiver FMR such as described in my parent application. The correcting circuit CC is added to reproduce an undistorted signal in jack J. That is, in Fig. 3 the signal frequencies to be corrected are applied to the primary winding of a transformer 50 and are impressed from the secondary winding of said transformer on the input electrodes 52, 54 of a thermionic tube 51 to energize the same. The control electrode 52 of tube 51 is maintained at the desired operating potential by means of a biasing source 55. The anode electrode 56 of tube 51 is connected through a parallel circuit comprising a resistance 57 and capacity 58 to the cathode 54 by way of a high potential charging source 59.

The low frequencies of the signal potentials are emphasized by means of the capacity 58 connected across the resistor 57. The impedance of this resistance 57 and capacity 58 in parallel is high at the lower signal frequencies and low at the higher signal frequencies. The amplification factor of the tube 51, which depends upon the external impedance of its anode cathode circuit, will be high at the lower signal frequencies and low at the higher signal frequencies. The signal frequency oscillations appearing on the anode of tube 51 are impressed therefrom by way of a coupling condenser 60 to the control grid 61 of a thermionic amplifier 62. These distorted or corrected signal frequency potentials are amplified in 62 and appear in the primary winding 63

of the transformer winding 64. The corrected signal frequencies may be utilized from the secondary winding 65 of the transformer 63.

In order to operate 62 at the desired point on its characteristic curve, biasing potential is supplied from the source 66 by way of resistance 67 to the control electrode 61 of tube 62.

If the single distortion or correction tube 51 does not effect sufficient distortion or correction of the signal frequencies passed therethrough, a second tube, connected in circuit and operated similar to tube 51, may be connected in cascade with 51 to apply more distortion or corrective effect to the signal. This arrangement is shown in Fig. 4.

In Fig. 5 the signals to be corrected are impressed on the input winding of a transformer 50 and utilized from the secondary winding 65 of transformer 63 in the same manner as in the arrangement of Fig. 3. In Fig. 5, however, no amplifier is shown connected with the correction tube 51, although it is understood that the corrected signals can be further amplified, if necessary, by connecting the output of tube 51 with the input of a thermionic amplifier. The secondary winding of the transformer 50 is connected in parallel with the potentiometer resistance 70 in order that the desired signal amplitude may be impressed on the input electrode 52 by way of the tap 71.

In this arrangement the resistance R_2 is of such a high impedance to the signal current as compared to the impedance of the capacity C_2 to the signal current that the current passed through the circuits R_2 , C_2 is governed mainly by the resistance of R_2 . This makes the current through the circuit elements C_2 , R_2 constant with frequency so that the voltage across C_2 will be inversely proportional to the frequency of the applied signal, due to the fact that the impedance of the condenser C_2 varies inversely as the frequency of the signals applied across the terminals thereof vary. The potentials appearing at the terminals of C_2 are impressed on the input electrodes 52, 54 of correction tube 51.

In the arrangement shown in Fig. 6 correction is applied to the signal in the same manner in which correction is applied thereto by the arrangement shown in Fig. 5. However, in Fig. 6 a second tube 51' is added for the purpose of varying the amount of distortion or corrective effect applied to the signal waves relayed therethrough. When tube 51' is switched off full correction will be obtained by means of the tube 51 in the same manner in which correction is obtained in the arrangement of Fig. 5. With the tube 51' turned on, signal potentials the amplitude of which may be determined by the tap 71', will be applied from the parallel resistance 70' to the terminals of the resistance R_4 by way of resistance R_3 . The resistances R_3 , R_4 will affect all of the frequencies of the signal impressed thereon in like manner so that no corrective effect will be applied to the signal appearing on the input electrodes 52' of the tube 51'. Consequently, the oscillations at signal frequency, appearing on the anode 56' of tube 51' and applied therefrom to the transformer 64, will be the same for all frequencies and will represent in a normal manner the signal potentials applied at the input of the correction circuit.

By moving the taps 71 and 71' along the resistances 70 and 70', the amount of corrected signal and uncorrected signal reaching the output circuit 63 can be adjusted to give the desired

characteristic to the signal frequency in the output circuit, which characteristic may be somewhere between full correction of the signal and no correction.

- 5 This type of correction circuit is useful where it is desired that the transmitter radiate a combined frequency and phase modulated signal or a cross between frequency and phase modulated signal. Furthermore, such an arrangement is especially desirable where a correction circuit of this type is used in the signal amplifier circuits of the transmitter and a second correction circuit of this type is used subsequent to the detector in the receiver receiving signals from said transmitter.
- 10 In the correcting circuit shown in Fig. 7, as in the prior arrangements, the signals to be corrected are impressed on the transformer 50 and the corrected signals are utilized from the transformer 64. In this arrangement, however, a different means is provided for emphasizing the lower frequencies of the signal. The value of the inductance XL in series with the control electrode is so chosen that its impedance to the signal frequency is high as compared to the impedance of the resistance R_5 to the signal frequencies. The inductance XL then is the governing factor of the circuit and determines the intensity of the current passed through the circuits I , R_5 . Since the inductance XL offers a higher impedance to the higher frequencies than to the lower frequencies, the current passing through the inductance XL will be inversely proportional to the frequency of the impressed signals. Consequently, the voltages at signal frequency, appearing across the resistance R_5 , which are fed to the control electrode 52 of tube 51, will be inversely proportional to the frequency of the impressed signals.

Having thus described my invention what I claim is:

1. The method which includes these steps, amplifying each of the components of a band of frequencies an amount inversely proportional to its frequency, amplifying each of the components of said band of frequencies an amount which is constant with frequency, and combining the amplified wave portions.

2. The method which includes these steps, amplifying the components of a complex signaling wave an amount such that the amplified wave varies inversely with frequency, amplifying the components of said complex signaling wave an amount such that the amplified wave is constant with frequency, combining the amplified waves and modulating the instantaneous frequency of a high frequency carrier wave in accordance with the combined waves.

3. The method of signaling with a high frequency carrier wave and signaling waves which includes the steps of amplifying said signaling wave in a way such that the amplified wave varies between a characteristic which is flat or constant with frequency and a characteristic which is inversely proportional to frequency and modulating the high frequency carrier wave in accordance with the amplified wave.

4. In an amplifying system for wave energy covering a given band of frequencies, a pair of amplifying stages each having input circuits and output circuits, connections for supplying said wave energy covering said band of frequencies, to the input circuits of said amplifiers and means combining the amplified wave energies of said amplifying stage output circuits, the amplifier stages being so arranged and operated that one

of said stages has a characteristic such that its output varies inversely with input frequency and the other of said stages has a characteristic such that its output is constant with respect to input frequency.

5. An amplifier comprising a pair of discharge tube systems each having an anode, a cathode and a control electrode, means connecting the anodes effectively in parallel, an input circuit connected between the control grid and cathode of one of said tube systems having a characteristic such that its output is inversely proportional to frequency, another input circuit connected between the control grid and the cathode of the other tube system having a characteristic such that its output is constant with frequency, a source of wave energy to be amplified, said wave energy covering a predetermined band of frequencies and means for feeding wave energy covering said predetermined band of frequencies from said source through each of said input circuits to each of said tube systems.

6. Apparatus as claimed in the preceding claim characterized by the fact that a wave amplitude attenuator is provided in at least one of said input circuits to relatively variably control the amount of the wave energy fed to the input circuits of said tube systems.

7. The method of signaling which includes these steps, amplifying components of an entire band of wave energy characteristic of a complex signaling wave an amount which is substantially inversely related to the frequency of the various components, substantially uniformly amplifying components of said entire band of wave energy characteristic of said complex signaling wave, and combining the amplified waves.

8. The method of signaling by means of a high frequency carrier wave and a complex signaling wave which includes these steps, amplifying components of an entire band of wave energy characteristic of said complex signaling wave an amount which is substantially inversely related to the frequency of the various components, substantially uniformly amplifying the components of said entire band of wave energy characteristic of said complex signaling wave, combining the amplified wave and modulating the instantaneous frequency of said high frequency carrier in accordance with the combined amplified waves.

9. The method of operating with modulating potentials covering a band of frequencies which includes these steps, amplifying the potentials of said band of frequencies an amount substantially inversely proportional to their frequencies, amplifying the potentials of said band of frequencies an amount which is substantially uniform over the band, and combining the amplified potentials to derive modified modulating potentials.

10. The method of operating with modulating potentials covering a band of frequencies which includes these steps, amplifying the potentials of said band of frequencies an amount substantially inversely proportional to their frequencies, amplifying the potentials of said band of frequencies an amount which is substantially uniform over the band, combining the amplified potentials, and relatively adjusting the amount of amplification accomplished in said two amplifying steps to obtain modified modulating potentials.

11. The method of operating with wave energy of carrier wave frequency and modulating potentials covering a band of frequencies which includes these steps, amplifying the potentials of said band of frequencies an amount substantially inversely proportional to their frequencies, amplifying the potentials of said band of frequencies an amount which is substantially uniform over the band, combining the amplified potentials to derive modified modulating potentials and modulating the instantaneous frequency of the wave energy of carrier wave frequency in accordance with the derived modulating potentials.

12. The method of operating with wave energy of carrier wave frequency and modulating potentials covering a band of frequencies which includes these steps, amplifying the potentials of said band of frequencies an amount substantially inversely proportional to their frequencies, amplifying the potentials of said band of frequencies an amount which is substantially uniform over the band, combining the amplified potentials, relatively adjusting the amount of amplification accomplished in said two amplifying steps to derive modified modulating potentials and modulating the instantaneous frequency of said wave energy of carrier wave frequency in accordance with the derived modulating potential.
